UNITED STATES PATENT OFFICE

CLYDE W. JOHNSON, OF SAUGUS, MASSACHUSETTS, ASSIGNOR TO DEWEY AND ALMY CHEMICAL COMPANY, OF CAMBRIDGE, MASSACHUSETTS, A CORPORATION OF MASSACHUSETTS

COVER LINING APPARATUS

Application filed October 12, 1928. Serial No. 312,190.

This invention pertains to cover or cap lining apparatus designed to apply a marginal band of lining compound to the inner surface of a receptacle cover or cap, and relates more particularly to means for moving a distributing nozzle or nozzles in a predetermined path relatively to a cover or cap; to means for supporting and, in some cases, for rotating the cover or cap during the application of the lining compound; and to means for coordinating the movement of the nozzle, cover-supporting means, and a valve for controlling the distribution of the compound.

The present arrangement has certain advantages over those in which the cover is moved relatively to a stationary nozzle, particularly in that it facilitates the automatic lining of a cover or cap of large diameter or of non-circular contour, for example rectangular. The mechanism of the present invention is capable of applying lining compound rapidly and accurately to covers or caps of a wide range of sizes and in certain embodiments to covers of almost any contour, whether bounded by straight or curved lines or combinations thereof, and is preferably so designed as to apply the compound at a substantially uniform linear rate of speed regardless of the shape of the cover, thus ensuring the deposit of lining compound in a band of uniform width and depth.

In the accompanying drawings I have illustrated certain desirable embodiments of the invention by way of example but wish it to be understood that the invention, in so far as its broader principles are concerned, is not to be restricted to the specific mechanism here illustrated but is capable of embodiment in equivalent mechanism and without reference to the precise proportion of parts, the specific arrangement of parts, or the particular adjunctive elements to be employed therewith.

In the drawings

Fig. 1 is a front elevation, with certain parts broken away, showing one desirable embodiment of the present invention for

applying lining compound to circular covers;

Fig. 2 is a fragmentary vertical section to larger scale, substantially on the line 2-2 of Fig. 1;

Fig. 3 is a horizontal section substantially on the line 3-3 of Fig. 1, certain parts being omitted;

Fig. 4 is a fragmentary horizontal diagrammatic section, substantially on the same plane as Fig. 3, but illustrating a modified form of apparatus and omitting certain parts;

Fig. 5 is a diagrammatic fragmentary horizontal section illustrating means for rotating the chuck shaft in lining a rectangular cover;

Fig. 6 is a fragmentary diagrammatic plan showing other means for rotating the nozzle;

Fig. 7 is a diagrammatic plan view showing a plurality of nozzles arranged to line different portions respectively of the same cover; and

Fig. 8 is a section on the line 8-8 of Fig. 4.

Referring first to Figs. 1, 2 and 3, the invention is shown as embodied in a machine comprising a frame which consists of a hollow box-like base casting 1 mounted upon legs of convenient height, such casting being provided with bearings 2 and 3 on its opposite sides forming journals for the horizontal drive shaft S. This shaft projects out through the side of the frame and may be provided with a pulley or other drive element, not shown.

The box-like frame member 1 is preferably provided with a substantially horizontal top member or table 4, and this top member supports a pair of spaced substantially vertical bearing brackets 5 and 6, integral if desired with the part 4, providing journal bearings for vertical shafts 7 and 8 respectively. These shafts are furnished at their lower ends with beveled gears 9 and 10 meshing with beveled gears 11 and 12 respectively fixed to the shaft S, the arrangement being such that the shafts 7 and 8

65

69

65

70

70

80

85

89

95

100

turn at the same speed and in the same direction.

Substantially horizontal crank disks 13 and 14 are secured to the upper end of the shafts 7 and 8 respectively. These disks (Fig. 3) are preferably provided with radial slots 15 and 16 respectively, the disks with their drive gears being so arranged that the slots 15 and 16 are always similarly oriented.

Brackets 18 and 19 are adjustably mounted within the slots 15 and 16 respectively, said brackets being secured in adjusted position by means of bolts 20 and 21 respectively (Fig. 1). The brackets 18 and 19 carry upstanding crank pins 22 and 23 respectively, said pins being received in journal openings in the opposite ends of an elongate nozzle-supporting bar 24. This bar is preferably provided at a point substantially midway between its ends with an elongate slot permitting adjustment of a nozzle 25 which is mounted therein. While the slot and the central arrangement of the nozzle is preferable, this precise arrangement is not necessary, since the simultaneous rotation of the crank pins 22 and 23 by the gearing above described causes a bodily movement of the bar 24 in which every element of the bar describes a circle of a radius equal to the distance of the crank pins from their centers of revolution, it being understood that the crank pins are adjusted to equal distances from their centers.

The distributing nozzle 25 may be of any suitable and usual type and is supplied with cover lining compound by means of a flexible conduit 26 leading from an elevated tank 27. The nozzle is furnished with a normally closed valve for controlling the delivery of the lining compound and this valve is actuated as hereinafter described by means of a flexible wire or other suitable connection 28.

The tank 27 may, if desired, be mounted upon an elevated shelf 29 supported upon posts 30 and 31 rising from the base portion of the frame. The shelf 29 also supports a pair of bearing brackets 32 and 33, respectively, providing journal bearings for a substantially horizontal shaft 34. This shaft is furnished at one end with a sprocket wheel 36 which is driven by means of a chain 37 engaging a sprocket wheel 38 fixed to the shaft S. Preferably the sprocket wheel 36 is loose on the shaft 34 but may be connected thereto by means of a clutch 39 (preferably of one revolution type) operated by means of a lever 40 and a rod 41 leading downwardly to a suitable handle or treadle, not shown, for convenient actuation by the operator.

The shaft 34 carries a cam 42 (Figs. 1 and 2) engaging a cam follower roll 43

mounted on a lever 44 fulcrumed at 45 in a bracket 46 mounted on the shelf 29. Preferably the rear end of the lever 44 rests upon a spring actuated plunger 47 tending constantly to hold the roll 43 in engagement with the cam 42. The forward end of the lever 44 is preferably forked at 48 and engages between fixed collars on a rod 49 vertically movable in a suitable guide member 50 at the front edge of the shelf 29. The valve actuating wire 28 above referred to is attached at its upper end to the lower end of the rod 49 so that, whenever the cam follower roll 43 is depressed by direction of the cam 42, the wire 28 is pulled to open the valve in the nozzle 25.

The shaft 34 also carries a cam 51 engaging a follower roll on a lever 52 fulcrumed at 53 on the bracket 46, and the rear end of the lever 52 is connected, by means of a link 54, to the rear arm 55 of a lever fixed upon a shaft 56 turning in bearings in brackets 57 and 58 projecting downwardly from the under side of the table 4. The forward arm 59 of this lever preferably is forked as indicated at 59^a, 59^b (Fig. 1) and supports a ball bearing collar 60 embracing a shaft 61 journaled in a bearing 62 carried by a bracket 62^a depending from table 4. The upper part of shaft 61 is housed in a sleeve 61^a arranged to rotate and to slide vertically in a bearing 61^b carried by the table 4. The sleeve 61^a telescopes over shaft 61 and is splined to the latter. The lower end of the sleeve 61^a rests upon the ball bearing collar 60 and the sleeve is furnished with a collar or flange 62 supporting the lower end of a spring 63, whose upper end engages a shoulder on the bearing 61^b, the spring thus normally tending to depress the sleeve 61^a and at the same time to hold the roll on lever 52 in operative engagement with the cam 51.

A cover-supporting chuck 64 (Fig. 3) is mounted on the upper end of the sleeve 61^a above the upper surface of the table 4. This chuck 64 may be of any suitable contour and is provided with a plurality of dogs 65 adapted to engage the edge of the cover or cap C to be lined. Preferably the chuck 64 is provided with divergent channels or slots 66 in which the dogs 65 are adjustably mounted so as to permit the chuck to be used for holding covers of a wide range of sizes and to permit accurate centering of the cover with respect to the path of the nozzle.

The lower end of the shaft 61 carries a beveled gear G which is always in mesh with a beveled gear G¹ fixed on shaft S. Preferably the gears G and G¹ are so arranged as to turn the shaft 61 oppositely to the shafts 7 and 8. Preferably the gear G¹ is normally loose on the shaft but may be connected thereto for driving by means of a clutch K which is actuated by means of a cam on the end of an arm K¹ connected to

the shaft 56. While I may thus provide for rotation of the shaft 61 during the lining operation, it may be desirable under some circumstances to dispense with such rotation of the shaft, and this may be accomplished by permanently disconnecting the clutch K, or by omission of the gears G and G¹ as may be preferred.

In the modified arrangement shown in Fig. 4 it is assumed that the machine is of the general construction above described except for the specific means for moving the nozzle or nozzles in the desired path. In this arrangement the table 4^a is provided with parallel rails 70 forming a rectilinear guideway for a carriage 71. This carriage is furnished with a pin 72 projecting downwardly through a slot in the table into engagement with an actuating groove 74 in a rotating cam drum 73.

The table 4^a is also provided with a second pair of spaced parallel rails 75 arranged at right angles to the rails 70 and furnishing a guideway for a secondary carriage 76. This carriage is also provided with a downwardly projecting pin 77 engaging a slot 78 in a cam 79. The cams 73 and 79 are here shown as cylindrical drum cams, but it is to be understood that cams of other type may be employed for the purpose. These cams are driven in synchronism by means of suitable gearing, not shown, but preferably comprising intermeshing beveled gears of a type common in the arts. And the cam paths are preferably so designed as to ensure uniform linear speed of the nozzle or nozzles relative to the surface of the cover, including the corners of angular covers, so that a uniform band of lining compound will be deposited at all parts of the margin of the cover.

The carriage 76 supports a pair of spaced parallel rails 80 forming a guideway substantially at right angles to the path of movement of the carriage 76. This guideway receives a pin 81 projecting downwardly from a carriage 82 sliding in a rectilinear guideway defined by spaced rails 83 mounted on the primary carriage 71. The guideway defined by rails 83 is at right angles to the path of movement of the primary carriage 71, and the carriage 82 supports an elongate bar 84 also extending at right angles to the path of movement of the carriage 82 and preferably provided with an elongate slot or slots 85 for the reception of the nozzle or nozzles 86. The outer end portion 87 of the bar 84 may be supported in any desired manner, for example by means of a swivel roller or ball 88 resting upon the upper surface of the table 4^a.

In lining covers of non-circular shape, for example rectangular, it may also be desirable, although not always necessary, to rotate them during the lining operation,

and this may be accomplished by means such as shown diagrammatically in Fig. 5, for example. In this figure the shaft 61 which drives the chuck, as above described, is provided with a spur gear G³ of a contour similar to that of the cover to be lined. This gear meshes with a spur pinion G⁴ carried by an arm G⁵ pivoted to swing about a shaft G⁶ as a center. A sprocket chain G⁷ transmits movement from the shaft G⁶ to the pinion G⁴. A spring G⁸ keeps the pinion G⁴ constantly in mesh with the gear G³. The shaft G⁶ is driven in timed relation to the cams 73 and 79 by means of any suitable mechanism, not shown. The gear G³ is preferably removable from the shaft 61 to permit its replacement by gears of other shapes and sizes (including circular gears) according to the shape of the cover to be lined.

The operation of the device shown in Figs. 1 to 3 inclusive is substantially as follows, it being assumed that normally the shaft 34 is stationary, the valve in the nozzle 25 is closed, the cover supporting chuck 64 is in its lowermost or inoperative position as shown in Fig 1, and that the shaft S is continuously operating to turn the cranks 22 and 23 in synchronism, thus bodily moving the bar 24 and causing the nozzle 25 to describe the circular path whose radius is equal to the distance of one of the cranks from its center of rotation.

The dogs 65 having been adjusted so as to center a cover with reference to the path of rotation of the nozzle, a cover is (either manually or by appropriate mechanical means) placed upon the chuck with its edges in engagement with dogs 65. The operator then moves the rod 41 to clutch the sprocket wheel 36 to the shaft 34 thereby causing the cams 42 and 51 to rotate. These cams are so timed that the lever arm 69 is first elevated to raise the cover holding chuck into operative position with the cover disposed in a plane immediately below the delivery end of the nozzle 25 and simultaneously clutching gear G¹ to shaft 4, thereby rotating the chuck and the cover, and while the chuck is held in this elevated position by an appropriate dwell on the cam 51, the cam 42 opens the valve nozzle by actuation of the wire 28, thus permitting discharge of lining compound from the nozzle. The timing of the parts is preferably such, as determined by the ratio of the sprockets 36 and 38, that the nozzle will make several complete circuits of the cover while the chuck is in elevated position and the valve is open, thus insuring the delivery of a continuous band of the lining compound to the marginal portion of the cover, the rotation of the cover causing the lining compound to flow centrifugally into close contact with the cover rim. When lining

- covers of certain types the rotation of the chuck may not be necessary and by removing gears G , G^1 , or permanently disengaging clutch K such rotation may be stopped.
- 5 At the end of a sufficient and predetermined number of revolutions of the nozzle the valve is closed by further movement of the cam 42 and the chuck 64 is permitted to return to its inoperative position by the action 10 of the cam 61. The clutch 39 is now disengaged automatically or manually, and the cover is removed from the chuck by hand or appropriate mechanical means. A new cover is now embodied and the above 15 sequence of operations is repeated.
- With the arrangement shown in Fig. 4, which is particularly intended for use in lining covers of other than circular contour, although capable of lining circular covers 20 as well, the cam grooves 74 and 78 are so designed as to impart the desired coordinates of motion to the carriages 71 and 82 whereby to cause the nozzle-supporting member 84 to move bodily in such manner that every 25 element of said nozzle-supporting member describes a path corresponding to the shape of the cover to be lined. Thus by the provision of appropriate dwells in the cams the member 84 may be caused to move in a 30 rectilinear path, either horizontally or vertically as viewed in Fig. 4, during which but one of the cams 73 or 79 is active, or by an appropriate combination of active portions of the two cams the member 84 with its 35 nozzle may be caused to describe circular or other curved paths of movement. It is thus readily possible to line a cover of a contour such as indicated at C^1 (Fig. 4) having substantially straight sides united by curves or 40 arcuate portions, the cover being rotated if desired by the mechanism of Fig. 5.

As shown in Fig. 4 the member 84 is arranged to support a plurality of nozzles 86 so that several covers may be lined at once, 45 it being understood that in the same way the nozzle-supporting bar 24 of Figs. 1 to 3 inclusive may carry a plurality of nozzles with provision of appropriately formed chucks in each instance adapted to support a 50 similar number of covers.

In place of the mechanism shown in Fig. 4 I may guide the nozzle (or nozzles), if desired by means of a fixed cam of desired contour with which a nozzle carrier is directly engaged. Thus as shown in Fig. 6 55 I may provide a cam plate 90, supported in a plane parallel to or coincident with the plane of the cover C^x (when the latter is in compound receiving position) and the nozzle 25^a is mounted on a carrier 91 having follower rolls 92 engaging the cam path 93 provided in the cam plate. The carriage 60 is provided with a driving arm preferably resiliently extensible (as for example consisting of telescoping spring pressed parts)

which is connected to a driving chain 94 or its equivalent, which passes about suitable guide sprockets 95 driven in time with the other parts of the machine by suitable mechanism. The cam path 93 has a contour similar to that of the cover to be lined, and as the nozzle carrier is moved by the chain, the nozzle is constrained to follow the desired path. Obviously the nozzle may be mounted upon an adjustable arm on the 75 carrier 91 to permit it to follow covers of different sizes.

In Fig. 7 I have indicated diagrammatically an arrangement in which nozzles C^4 and C^5 are caused to travel first in one direction and then in the other a distance less than the entire distance around the cover. For example, each nozzle may move half way around the cover and then back again. This is readily accomplished, as in Fig. 4, 85 by the provision of a set of cams for each nozzle.

While I have herein disclosed certain desirable arrangements for moving the nozzle in closed paths of predetermined contour I 90 contemplate that other and equivalent means may be designed for the purpose and I wish it to be understood that all such means are to be considered as falling within the scope of the invention and defined by the appended claims.

I claim:

1. Apparatus for moving a distributing nozzle whereby to apply a lining compound to the marginal portion of a cover or cap, 101 said apparatus comprising a nozzle-supporting means movable in a plane, a nozzle on the nozzle-supporting means, and means for imparting to said nozzle-supporting means a movement in an orbit substantially coincident with the contour of the cover to be lined.

2. Apparatus for moving a distributing nozzle whereby to apply a lining compound to the marginal portion of a cover or cap, 110 said apparatus comprising nozzle-supporting means movable in a plane, a nozzle on the nozzle-supporting means, and means including two elements rotating in timed relation for imparting to said nozzle-supporting means a bodily movement in an orbit substantially following the contour of the cover to be lined.

3. Apparatus for moving a distributing nozzle whereby to apply lining compound to the marginal portion of a cover or cap disposed in a substantially horizontal plane, 120 said apparatus comprising a nozzle-supporting member movable in a substantially horizontal plane, a nozzle carried by the nozzle-supporting member, and means for supporting and moving said nozzle-supporting member in an orbit so that all points therein describe closed paths corresponding to the contour of the cover or cap to be lined.

4. Apparatus for moving a distributing nozzle whereby to apply lining compound to the marginal portion of a cover or cap disposed in a substantially horizontal plane, said apparatus comprising an elongate nozzle-supporting bar disposed in a substantially horizontal plane a nozzle carried by said bar and a pair of synchronously moving actuating members cooperating to impart bodily movement to the bar in a horizontal plane, said actuating members imparting such coordinates of motion to the bar as to cause the nozzle carried thereby to follow the contour of the cap or cover. 70
5. Apparatus for moving a distributing nozzle whereby to apply lining compound to the marginal portion of a cover or cap, said apparatus comprising a nozzle-supporting member having provision for adjustably mounting a nozzle thereon, a nozzle carried thereby and a plurality of synchronously rotating actuating members arranged to impart such coordinates of motion to the nozzle-supporting member as to cause the nozzle substantially to follow the contour of the cover. 80
6. Apparatus for moving a distributing nozzle whereby to apply lining compound to the marginal portion of a cover or cap, said apparatus comprising a nozzle-supporting member, a nozzle carried thereby, a pair of rotating cranks for moving said member, and means for simultaneously rotating said cranks whereby to impart bodily movement to the supporting member in such a path as to cause the nozzle carried thereby substantially to follow the contour of the cover. 90
7. Apparatus for moving a distributing nozzle whereby to apply lining compound to the marginal portion of a cover or cap, said apparatus comprising a nozzle-supporting member, a nozzle carried thereby, a pair of rotary cranks engaging said member, said cranks always being similarly oriented, and means for rotating said cranks synchronously at the same speed. 95
8. Apparatus for moving a distributing nozzle whereby to apply lining compound to the marginal portion of a cover or cap, said apparatus comprising a nozzle-supporting member, a nozzle carried thereby, a pair of rotary cranks engaging said member, means providing for adjustment of the radial distance of said cranks from their respective centers of rotation, and means for rotating said cranks synchronously at the same speed. 105
9. Apparatus for moving a distributing nozzle whereby to apply lining compound to the marginal portion of a cover or cap, said apparatus comprising a bar having provision for mounting the nozzle thereon intermediate its ends, a nozzle carried thereby by a pair of cranks engaging opposite ends respectively of the bar, said cranks being similarly oriented and at substantially equal distances from their centers of rotation, and means for rotating the cranks synchronously at the same speed whereby to move the nozzle mounted on the bar in a circular path of predetermined diameter. 110
10. Apparatus for moving a distributing nozzle whereby to apply lining compound to the marginal portion of a cover or cap, said apparatus comprising spaced crank disks turning in a horizontal plane, each disk having a radial slot therein, a crank pin adjustably secured in each slot, gearing for driving the crank disks synchronously at the same speed in the same direction, and an elongate bar whose opposite ends have journal openings receiving the respective crank pins, said bar having provision for mounting a distributing nozzle thereon. 120
11. Apparatus for moving a distributing nozzle whereby to apply lining compound to the marginal portion of a cover or cap, said apparatus comprising a chuck for holding the cover or cap, and means for moving the distributing nozzle bodily in an orbit conforming to the contour of the cover. 125
12. Apparatus for moving a distributing nozzle whereby to apply lining compound to the marginal portion of a cover or cap, said apparatus comprising a chuck plate having slots therein, dogs adjustably mounted to the slots for positioning a cover on the chuck, a distributing nozzle disposed above the plane of the chuck, and means for moving the nozzle in a path substantially similar to the contour of the cover. 130
13. Apparatus for moving a distributing nozzle whereby to apply lining compound to the marginal portion of a cover or cap, said apparatus comprising a vertically movable but normally stationary chuck for holding the cover or cap, a distributing nozzle, means for moving the nozzle in a horizontal plane to describe a path similar to the contour of the cover, and means for raising the chuck from normal cover-receiving position to a plane immediately below the plane of movement of the nozzle. 140
14. Apparatus for moving a distributing nozzle whereby to apply lining compound to the marginal portion of a cover or cap, said apparatus comprising a distributing nozzle movable in a substantially horizontal plane, means for moving the nozzle bodily in an orbit corresponding in outline to the contour of the cover, a cover-supporting chuck normally disposed in a plane substantially below the plane of movement of the nozzle, and cam means for raising the chuck to position the cover mounted thereon in operative relation to the nozzle. 150
15. Apparatus for moving a distributing nozzle whereby to apply lining compound to the marginal portion of a cap or cover, said apparatus comprising a distributing nozzle movable in a substantially horizontal plane, 160

means for moving the nozzle in a closed path corresponding in outline to the contour of the cover, a cover-supporting chuck normally disposed in a plane substantially below

5 the plane of movement of the nozzle, and cam actuated means for determining the delivery of lining compound from the nozzle.

16. Apparatus for moving a distributing nozzle whereby to apply lining compound to

10 the marginal portion of a cap or cover disposed in a substantially horizontal plane, said apparatus comprising a distributing nozzle movable in a substantially horizontal plane, means for moving the nozzle in a

15 closed path corresponding in outline to the contour of the cover, a cover-supporting chuck normally disposed in a plane substantially below the plane of movement of the nozzle, and means operating in timed relation

20 with the means for moving the distributing nozzle for raising the chuck to position the cover mounted thereon in operative relation to the nozzle and for determining the delivery of lining compound from the

25 nozzle.

17. Apparatus for moving a distributing nozzle whereby to apply lining compound to the marginal portion of a cover or cap disposed in a substantially horizontal plane,

30 said apparatus comprising a distributing nozzle movable in a substantially horizontal plane, means for moving the nozzle in a closed path corresponding in contour to that of the cover, a cover-supporting chuck nor-

35 mally disposed in a plane substantially below the plane of movement of the nozzle, a rotary cam shaft turning in synchronism with the means for moving the nozzle, cam

means mounted on the shaft for lifting the 40 chuck to operative position and for initiating the delivery of lining compound from the nozzle, and a one revolution clutch for driving the came shaft.

18. Apparatus for moving a distributing 45 nozzle whereby to apply lining compound to the marginal portion of a cap or cover, said apparatus comprising nozzle-supporting means movable in a plane, means for imparting to said nozzle-supporting means a move-

50 ment such that the nozzle describes a path substantially similar to the contour of the cover to be lined, and means for turning the cover in its own plane at a velocity differing from that of the nozzle-supporting

55 means.

19. Apparatus for moving a distributing nozzle whereby to apply lining compound to the marginal portion of a cap or cover, said apparatus comprising nozzle-support-

60 ing means movable in a plane, means for imparting to said nozzle-supporting means a movement such that the nozzle describes a path substantially similar to the contour of the cover to be lined, and means for rotating

65 the cover in a direction opposite to the

direction of rotation of the nozzle-supporting means.

20. Apparatus for moving a distributing nozzle whereby to apply lining compound to the marginal portion of a cap or cover, 70 said apparatus comprising nozzle-supporting means movable in a plane, means for imparting to said nozzle-supporting means a movement such that the nozzle describes a path substantially similar to the contour of the cover to be lined, and means operative, during the delivery of lining compound to the cover, for rotating the cover.

21. A machine for coating irregular shaped can ends comprising a coating nozzle, 80 a can end chuck for presenting a can end to said nozzle for coating and for holding said end stationary during coating, means for supporting said nozzle and for moving the same in a path conforming to the channel in the end to be coated, and a control valve for said nozzle.

22. A machine for coating irregular shaped can ends comprising a coating nozzle, 85 a can end chuck for presenting a can end to said nozzle for coating and for holding said end stationary during coating, means for supporting said nozzle and for moving the same in a path conforming to the channel in the end to be coated, a control valve for 90 said nozzle, a cam and devices operated thereby for opening the valve when the end is properly presented for coating and for closing the valve after the end has been coated.

Signed by me at Cambridge, Mass., this 8th day of Oct., 1928.

CLYDE W. JOHNSON.
